UNITED STATES PATENT OFFICE.

CHARLES A. BEHLEN, OF CINCINNATI, OHIO.

RUNNING-GEAR FOR VEHICLES.

SPECIFICATION forming part of Letters Patent No. 440,871, dated November 18, 1890.

Application filed March 27, 1890. Serial No. 345,477. (No model.)

To all whom it may concern:

Be it known that I, CHARLES A. BEHLEN, a citizen of the United States, residing at Cincinnati, in the county of Hamilton and State 5 of Ohio, have invented certain new and useful Improvements in the Running-Gear for Vehicles, of which the following is a specification.

While my invention relates generally to the 10 running-gear for vehicles, it applies more particularly to fifth-wheels, and has for its objects the addition of strength and durability, enabling the wheel to be applied not only to light vehicles, as at present, but also to the 15 heaviest class as well. Besides these features my improved fifth-wheel, while less expensive than others now in use, adds much to the finish of the vehicle to which it may be applied.

20 The advantages of the foregoing, as well as others to be hereinafter enumerated, will be apparent from the description herein contained, and by reference to the accompanying drawings, forming part of this application, in 25 which—

Figure 1 is a central longitudinal section taken through the front part of a vehicle, as a buggy, the rear portion not being shown. Fig. 2 is an enlarged top view of the bottom 30 portion of my fifth-wheel as it appears when attached to the head-block and axle, the upper segment being removed. Fig. 3 is a view showing the perforated lug on the axle-plate of the lower segment and the bottom axle- 35 plate for the reception of the duplex king-bolt. Fig. 4 is a front view of the spring, head-block, fifth-wheel, axle, and axle-bed, the whole being held together by the ordinary clips and nuts. Fig. 5 is a view showing 40 the various parts of my wheel disconnected, but in a line with one another, ready to be fastened in their proper positions. Fig. 6 is a central vertical section taken through the hub of the perch-plate and guard-iron in 45 a line with the king-bolt and shows my lock and wear-compensating washer in position. Fig. 7 shows modified shapes which can be given to the duplex king-bolt or retaining-pin so as to prevent its turning, as will be presentedly explained.

The letter A indicates the buggy-body, which is hung to the spring-bar Y by means of the body-loops L in the ordinary manner.

S represents an ordinary elliptic end spring, the leaves of which are indicated by the letters i n m. The body of the vehicle is represented as unloaded, carrying no weight.

B indicates the usual head-block, and C the axle-bed, while D is the axle.

E is the perch, which in this instance is a 60 double one.

F is the upper perch-plate, while G is the lower perch-plate and fifth-wheel stay or guard-iron combined.

H and I are the two segments which compose my fifth-wheel, H being the upper, while I is the lower. H is attached to the head-block B by means of the usual clips o h, which also embrace the spring S and hold it firmly in position on the head-block. The 70 ends of the clips pass through the ordinary perforated lugs l l on cross-plate T and are there held by nuts a, as indicated.

The ears e e on each end of the plate T are for the ordinary purpose—that of holding the 75 head-block securely in position conjointly with the clips o h.

Forming an integral part of cross-plate T is a depending shank P, which in turn is integrally united to the upper perch-plate F. 80 Below the point of union between the shank and said perch-plate the former may be hollowed out for the purpose of forming a socket, in which can rest the forward end of the perch itself, though this is not essential, but may be 85 found a convenient auxiliary. The end of the shank P is designed to rest on the lower perch-plate G, as indicated more clearly in Fig. 1.

The under segment I of my fifth-wheel has 90 a cross-plate W, which is designed to rest on the top portion of axle-bed C.

I' is the under axle-plate, which is also provided with perforated lugs c c. By means of the clips 1 2 and nuts 3 4 this under segment is rigidly secured to the axle-bed and axle.

5 6 indicate the ears on the plate W, which embrace the axle-bed, while 7 and 8 indicate the perforated lugs on the said plates W and xee

H' , which receive my duplex king-bolt K . The exterior of this king-bolt conforms to the shape of the perforated lugs 7 8. This shape may be of any angular form, as shown 5 in Figs. 1, 2, and 5, or it may take the shapes, for instance, as seen in Fig. 7. In other words, its exterior should consist of some angular shape in order to prevent it from turning in its retainers. The top of this retaining-pin K is provided with a flange t , whereby the pin can be seated on the perforated lug 7. Above the flange t is a spindle p , whereon rests the plate T of the upper segment, while the lower portion of the retaining-pin has a 10 like spindle m' , which rests in the hub j of the combined guard-iron and lower perch-plate. The retaining-pin K is tubular throughout its length, and in this tubular portion fits the king-bolt proper, which is indicated by 15 the letter M , as seen in Figs. 2 and 6.

The under side of the lower segment I is provided with a peripheral shoulder or flange U , which fits into a correspondingly-shaped slot v in the head of the guard-iron G . The 20 said shoulder is more plainly indicated by the dotted lines in Fig. 2.

To compensate for the frictional wear of the parts around the bolt M without loosening or taking apart any of the work, I make use 25 of the washer X , which encircles the bolt M and occupies a position midway between the lock-nut 9 and the end of spindle m' . This compensating washer consists of a hollow spindle provided with a shoulder, as seen. 30 The spindle portion entering the recess in hub j , it will readily be seen that should any wear occur it can be easily taken up and compensated by screwing up the lock-nut 9, which impinges against the face of said shoulder, 35 thus tightening the said washer and accomplishing the result desired.

The various parts and the positions they occupy having been detailed, I will now proceed to explain the utility of my improvements. 40

By the use of the peripheral flange operating in the slot formed in the head of the guard-iron I am enabled to keep the segments in a line true to one another, thus preventing 45 an unequal strain on any part.

By using the plate H' , I afford a support for the axle that is much greater than is obtained by the use of the clip cross-pieces.

By using the tubular retaining-pin in connection with the bolt M , thus forming what I would term a "duplex king-bolt," together with the perforated lugs on plates W and H' , as well as the compensating washer X , I secure the parts firmly together, besides holding the 50 axle rigidly in its proper position. As before stated, this retaining-pin K can be made of any desired shape, the only qualification necessary being that its contour be such that it will prevent its twisting or turning in the embracing-lugs. A key—such as is shown in 55

Fig. 7—made to enter a slot in the perforated lug or lugs will answer the purpose admirably.

By using the wheel herein shown and described all the parts must break before rendering it useless—that is to say, the connection at the point where the perch is secured, that at the point where the head of the guard-iron and the top segment are bolted together, as also the duplex king-bolt fastening. All 70 these must fail before the parts are or can be rendered inoperative, which failure at one and the same time is very improbable. If but one of these connections remain, the use 75 of the device is practicable.

By the use of the solid and rounded depending shank I am enabled to bring the perch close to the axle and obtain a greater sweep or turn of the segments than heretofore.

The above are some of the principal features of my invention; but there are others which to those skilled in the art will readily be perceived.

It may be well to state here that should it 90 from any reason be deemed desirable the retaining-pin K may be cast integrally with the perforated lug 7 on cross-plate W , thus obtaining the same results as if the two parts were separate, as indicated in the drawings. 95

What I claim, therefore, and desire to secure by Letters Patent, is—

1. In a fifth-wheel, the duplex king-bolt consisting of the retaining tubular pin K , one of whose sides bears flat against the axle and 100 axle-bed, the bolt M , and its retaining-nut 9, in combination with the perforated lugs 7 8 on cross-plates W and H' , respectively, the combined guard-iron and perch-plate G , upper and lower segments H I , attached, respectively, in 105 the usual way, and depending shank P between upper perch-plate and cross-plate T of the upper segment, substantially as shown and described, and for the purposes specified.

2. A duplex king-bolt for a fifth-wheel, consisting of a tubular sheath K , provided with upper and lower spindles p m' , flange t , and the contained bolt M , in combination with the hub j on combined guard-iron and perch-plate G , retaining-lugs forming a part of cross-plates W and H' , the segments H I , and the depending solid shank behind the duplex king-bolt and midway between the perch-plate F and the integral cross-plate T of upper segment H , all substantially as shown and described, and for the purposes noted.

3. In a duplex king-bolt for a fifth-wheel, a compensating washer X , provided with a spindle which encircles the bolt M and finds lodgment in a recess of the hub j and against the lower spindle of pin K , in combination with the nut 9, which impinges against the outer face of said washer, substantially as shown and described.

4. In a fifth-wheel, the following elements: 130

the duplex king-bolt contiguous to and in the rear of the axle and retainers 7,8 on cross-plates W and H', respectively, in combination with segments H and I, the latter having a peripheral shoulder which operates in a slot on the combined perch-plate and guard-iron G, shank P, depending from cross-plate T, to-

gether with perch-plate F, all substantially as shown and described, and for the purposes specified.

CHARLES A. BEHLEN.
